UNITED STATES PATENT OFFICE.

RAYMOND I. HILL, OF ELYRIA, OHIO, ASSIGNOR, BY DIRECT AND MESNE ASSIGNMENTS,
TO THE HILL RUBBER HEEL COMPANY, OF ELYRIA, OHIO, A CORPORATION OF OHIO.

RESILIENT HEEL OR HEEL-LIFT.

1,328,564.

Specification of Letters Patent.

Patented Jan. 20, 1920.

Application filed September 26, 1917. Serial No. 193,233.

To all whom it may concern:

Be it known that I, RAYMOND I. HILL, a citizen of the United States, residing at Elyria, in the county of Lorain and State of Ohio, have invented certain new and useful Improvements in Resilient Heels or Heel-Lifts; and I do hereby declare the following to be a full, clear, and exact description of the invention, such as will enable others skilled in the art to which it appertains to make and use the same.

My invention relates to resilient heels or heel lifts to be attached to boots or shoes, and more particularly such devices made of rubber or rubber composition.

One of the objects of my invention is to increase the cushion effect of such devices, reducing or eliminating the jars experienced in walking with shoes equipped with ordinary heels or heel lifts. I also aim to produce a device which will realize the improved cushion effect and which at the same time will be convenient and cheap to manufacture. I also aim to use a minimum of material and to reduce the weight of the heels.

Other objects of my invention and the invention itself will be better understood from a description of an embodiment of the invention.

Figure 1 is a plan view of the attaching face of an embodiment of my invention. Fig. 2 is a plan view of the tread surface of the embodiment of my invention shown in Fig. 1, and Fig. 3 is a section through the line 3—3 of the embodiment shown in Fig. 1.

Referring now to the drawing and to the embodiment of the invention shown therein, at 4 is shown the body portion of the heel lift made of some resilient material preferably of rubber or rubber composition, and which has the outline of a shoe heel. The thickness of the embodiment shown in the drawing is that of about three lifts of leather, though it will be readily understood that the thickness of the lift may be varied as desired. In the embodiment shown the tread surface 5 is shown as substantially flat, but the attaching surface 6 is shown concave and provided with a raised margin 7 on the edge thereof, which permits a certain amount of trimming of the lift to fit shoes of various sizes and also admits of a certain amount of compression to seal the edge of the seam between the rubber and the leather.

A plurality of members 8 project from the attaching surface of the heel. These members yield when weight is placed upon the heel, aiding in the cushioning effect of the resilient material. The utility of the device is greatly increased by placing the tops 9 of the members 8 all in substantially the same plane, so that the top of each member will always engage the part of the shoe to which the heel is attached, insuring better 60 coöperating action of all of the members in producing this cushioning effect.

In the embodiment shown the members 9 are webs running in different directions across the attaching face of the heel, but extending only part way across, a space 10 being left at the margin all about the heel to permit a certain amount of trimming of the lift to fit the shoe heel without injuring the projecting members. A plurality of cells 75 are thus formed in the attaching surface of the lift in which air is trapped and which aids in the cushioning effect of the projections. In the embodiment shown these webs run diagonally across the attaching surface 80 of the heel, some at right angles to others, thus forming square cells, though it will be obvious that any suitable shaped cells may be employed. Of course, the number of cells, the thickness and the strength of the 85 projections, as well as the shape of the projections may be varied without departing from the spirit of my invention.

Openings are shown at 14 through which nails or screws are applied to attach the 90 heel section to the shoe. When nails or screws are applied, the margin 7 should be slightly compressed so that in endeavoring to return to normal position, it tends to keep closed the edge of the seam between 95 the rubber and leather sections.

I have found by actual experiment that the cushioning effect of the heel is greatly increased over that of the ordinary rubber heel or heel lift. Plugs 11 may be used. I 100 prefer to make them of cork, though any suitable material and any suitable number of plugs may be employed.

As will be appreciated, the lift can be made in molds in the usual manner. Owing 105 to the recesses formed between the projections, I am able to reduce the weight of the heels as well as the amount of stock required to make them.

I have shown this particular embodiment 110

of my invention and these details for the purpose of describing the invention. It will be understood that many departures may be made from both the form and details without departing from the spirit of the invention.

I claim:

1. A resilient heel or heel section having a concave attaching face which is provided with upstanding yieldable intersecting webs substantially normal to the tread face, the webbed portion being substantially centrally and symmetrically disposed with reference to the margin of the heel. 10
2. A resilient heel or heel section having a concave attaching face which is provided with closely associated intersecting yieldable webs extending at substantially right angles to one another and to the tread face of the heel, the webbed portion being substantially centrally and symmetrically disposed with reference to the transverse short axis of the heel. 15
3. A resilient heel or heel section having a concave attaching face which is provided with upstanding intersecting webbing, the webbed portion conforming substantially to the shape of the heel or heel section and being substantially symmetrically disposed with reference to the transverse central axis 25 of the heel. 30
4. A resilient heel or heel section having a concave attaching face which is provided with upstanding intersecting webs substantially normal to the tread face, the webbed portion conforming in outline substantially to the outline of the heel or heel section and substantially symmetrically disposed with reference to the transverse central axis of the heel and there being an unwebbed marginal portion outside of the webbed portion. 35 40

In witness whereof I have hereunto set my hand this 24 day of September, 1917.

RAYMOND I. HILL.
